A. J. ADAMS.

PERAMBULATOR.

APPLICATION FILED FEB. 12, 1919.

1,379,295.

Patented May 24, 1921.

UNITED STATES PATENT OFFICE.

ARTHUR J. ADAMS, OF BAY CITY, MICHIGAN, ASSIGNOR TO THE FULTON COMPANY,
OF BAY CITY, MICHIGAN, A CORPORATION OF MICHIGAN.

PERAMBULATOR.

1,379,295.

Specification of Letters Patent.

Patented May 24, 1921.

Application filed February 12, 1919. Serial No. 276,585.

To all whom it may concern:

Be it known that I, ARTHUR J. ADAMS, a citizen of the United States, residing at Bay City, in the county of Bay and State of Michigan, have invented a new and useful Improvement in Perambulators, of which the following is a specification.

This invention relates to perambulators, particularly of the type illustrated in Adams 10 Patent No. 1,271,986, granted July 9, 1918.

The primary object is to provide an improved and simplified construction which can be manufactured at moderate cost.

A further object is to provide a practical 15 construction whereby the handle of the perambulator may be readily removed for shipping purposes, and may be applied with facility by the dealer or user after shipment.

The invention is illustrated in its preferred embodiment in the accompanying 20 drawings, in which—

Figure 1 represents a broken elevational view of a perambulator constructed in accordance with the invention; Fig. 2, a sectional view taken as indicated at line 2 of Fig. 1; Fig. 3, a broken sectional view taken as indicated at line 3 of Fig. 2; and Fig. 4, a vertical transverse section taken as indicated at line 4 of Fig. 1.

30 In the construction illustrated, A represents a running-gear frame equipped with a handle A¹; and B, a body mounted on the running-gear frame.

The frame A comprises a pair of axles 35 1 which are provided at their ends with spindles 1^a upon which the wheels (not shown) are journaled in the usual manner; a pair of upper longitudinal reach-members 2 and 2^a whose ends are extended beyond 40 the axles to afford spring-supports; a pair of lower longitudinal reach-members 3 and 3^a disposed in the same longitudinal planes as the corresponding upper reach-members 2 and 2^a, the squared portions of the axles 45 being interposed between the upper and lower reach-members; and rivets 4 securing the upper reach-members, the lower reach-members, and the interposed axles together.

50 The invention finds a useful application to baby-carriages employing a reed body, or a body of the character illustrated in the above-mentioned patent.

The body B may, however, be of any suitable construction.

In this type of construction, the handle is long and is sometimes formed integrally with the reach-members and connected by suitable braces to the running-gear frame. In the present construction, it is proposed 60 to provide a readily detachable handle and utilize the rear spring-supports of the running-gear frame as supports for the detachable handle. The reach-members of the running-gear frame are preferably tubular 65 members; and the front ends of the upper reach-members 2 and 2^a are provided with upwardly curved front extensions, affording front spring-supports 2^b, and are also provided with upwardly curved rear extensions 70 affording spring-supports 2^c.

The body B has its bottom equipped with depending U-shaped brackets 5 and 5^a, which are alike and which are connected with the bottom of the body near opposite 75 lateral edges thereof. Leaf-springs 6 and 6^a connect the front portions of the brackets with the front spring-supports 2^b; and similar leaf-springs 7 and 7^a connect the rear end portions of the brackets with the 80 rear spring-supports 2^c. The front and rear springs are shown as separately formed but obviously might be formed integrally with each other, if desired. The springs are formed to provide double reverse curves, 85 as shown, and the outer ends of the springs are connected, preferably by rivets 8, to the front and rear spring-supports of the running-gear frame. The tubular members forming the spring-supports are provided 90 with caps 9, giving a finished appearance.

The upper and lower reach-members are equipped just back of the rear axle with clips 10 which afford sockets for the lower ends of the bars of the handle A¹. There 95 is such a clip connecting the reach-members 2 and 3, and another like clip (not shown) connecting the reach-members 2^a and 3^a. Each clip 10 may be formed of a plate or strip of sheet-metal which is suitably curved and folded on itself to provide a tubular portion 10^a and upwardly extending arms 10^b which are curved at their extremities to embrace the upper reach-member. The front portion of the tubular part 10^a receives 100 the rear end of the lower reach-member, and is secured thereon by a rivet 11. The extremities of the arms of the clip are secured to the upper reach-member by a rivet 12.

The handle A¹ comprises a pair of arms 110

- or bars 13 and 13^a, which, of course, are connected at their upper ends by a transverse bar (not shown), affording a handle grip. The side members or arms of the handle are 5 of tubular form. The lower end portions are curved, as indicated at 13^b, to correspond with the curvature of the rear spring-supports 2^c and the extremities of the arms 13 and 13^a fit into the sockets afforded by the 10 rear portions of the tubular members 10^a of the clips 10, where they are detachably secured by bolts 14 which pass through the sockets and the inserted ends of the side members of the handle. The rear spring-supports 2^c are fitted with U-shaped clips 15 whose arms embrace the members 2^c and are secured thereto by rivets 16, as shown in Fig. 2. The clip 15 affords an attaching lug 15^a with which is detachably connected, by 15 means of a bolt 17, a clamping-ring 18 which is applied to the side bar of the handle at a height corresponding with the height of the clip 15, or preferably adjacent the upper end of the spring-support 2^c.
- 25 The meeting line of the lower reach-member and the side bar of the handle is indicated by the dotted line 19 in Fig. 1, it being understood that the ends of the side members of the handle are received in the sockets 30 10^a and abut against the rear ends of the lower reach-members of the running gear frame. To disconnect the handle, it is necessary only to remove the bolts 14 and 17. Nevertheless, the construction is thoroughly 35 staunch and durable. The handle is supported and braced by the spring-supports 2^c, so that other braces are unnecessary. The manner of extending and forming the upper reach-members of the running-gear frame 40 provides opportunity for interposing leaf-springs between the body and the spring-supports which are of ample length to give the desired resilience; and the springs may be securely attached, at slight cost, in the 45 manner indicated.
- The construction described is simple, cheap and presents an attractive appearance.
- The foregoing detailed description has 50 been given for clearness of understanding only, and no unnecessary limitation should be understood therefrom, but the appended claims should be construed as broadly as permissible in view of the prior art.
- 55 What I regard as new and desire to secure by Letters Patent is—
1. The combination of a running-gear frame equipped with axles and provided with spring-supports which extend rearwardly and upwardly from the rear axle, 55 sockets permanently connected with the running-gear frame in the rear of the rear axle, a handle having side bars, whose lower ends extend into said sockets and are detachably connected therewith, clips permanently connected with the upper portions of said spring-supports, and devices mounted on the side bars of the handle and detachably connected with said clips. 70
  2. The combination with a running-gear frame comprising a pair of axles, upper reach-members disposed above said axles and having their rear ends extended and curved upwardly to afford handle-supports, a pair of lower reach-members disposed below said axles and terminating a short distance in the rear of the rear axle, and means securing said reach-members to the interposed axles, of clips permanently attached to the upper and lower reach-members in the rear of the rear axle and affording sockets, a handle having side bars extending into said sockets, detachable connections between said side bars and said sockets, and means detachably connecting the side bars of the handle with the supports afforded by said extensions of the upper reach-members. 75
  3. The combination with a running-gear frame comprising a pair of axles, upper reach-members disposed above said axles and having their rear ends extended and curved upwardly to afford handle-supports, a pair of lower reach-members disposed below said axles and terminating a short distance in the rear of the rear axle and means securing said reach-members to the interposed axles, of clips permanently secured to the upper portions of said supports and affording attaching lugs, and clamping rings mounted on the side bars of the handle and detachably connected with said lugs. 80
  4. The combination with a running-gear frame comprising a pair of axles, a pair of upper reach-members surmounting said axles and having upwardly curved rear extensions affording supports for a handle, a pair of reach-members disposed below said axles and terminating a short distance in the rear of the rear axle, and means securing said reach-members to the interposed axles, 85 of clips provided with tubular members whose front portions receive the rear ends of the lower reach-members and provided with arms which embrace and are riveted to the upper reach-members, rivets securing the front portions of said tubular members to the rear ends of the lower reach-members, a handle provided with side bars whose lower ends extend into said tubular members, bolts connecting said side bars with said tubular members, and clamping devices detachably connecting the upper end portions of said supports with the side bars of the handle. 90
  5. The combination with a running-gear frame comprising a pair of axles, a pair of rigid reach-members mounted thereon and provided with upwardly curved rigid front extensions and upwardly curved rigid rear extensions affording spring-supports, a body 95

equipped at its lower side with brackets, and leaf-springs secured to said body and having extremities connected with the upper portions of said spring-supports.

5 6. The combination with a running-gear frame comprising a pair of axles, a pair of reach-members mounted thereon, and provided with upwardly curved rigid front extensions and upwardly curved rigid rear extensions affording spring-supports, a body equipped at its lower side with brackets, and double reverse curved leaf-springs connected with said brackets and having extremities connected with the upper portions of

15 said spring-supports.

7. In a perambulator, the combination of a pair of axles, tubular members connecting said axles and having their rear end-positions

extending rearwardly and upwardly from the rear axle to afford handle-supports, 20 a handle having side bars detachably connected at their lower ends with said tubular members adjacent the rear axle, and means detachably connecting said side bars with the upper portions of said handle-supports. 25

8. In a perambulator, the combination with a running-gear frame provided in the rear of the rear axle with upwardly extending tubular handle-supports, and a handle having side bars detachably connected with 30 the running-gear frame at points near the rear axle and detachably connected with said handle-supports near the upper ends thereof.

ARTHUR J. ADAMS.
